Patented Feb. 23, 1971

219,963

DUMP VEHICLE

D. E. McCraw, Jr., Charlotte, N.C., assignor to General Underground Equipment Company, Inc., doing business as General Hydraulics Company, Charlotte, N.C., a corporation of North Carolina

Filed July 1, 1969, Ser. No. 18,008

Term of patent 14 years

Int. Cl. D12—09

U.S. Cl. D14—3

FIG-1

FIG-2

FIG. 3

FIG. 4

FIG. 1 is an isometric view of the front of the vehicle showing my new design with the dump bed in lowered position;

FIG. 2 is an elevational view of one side of the vehicle, with the dump bed in raised position, the opposite side of the vehicle being identical to the side shown in FIG. 2;

FIG. 3 is a front view of the vehicle; and

FIG. 4 is a rear view of the vehicle.

I claim:

The ornamental design for a dump vehicle, substantially as shown and described.
